UNITED STATES PATENT OFFICE.

BENJAMIN F. KLASS, OF NEW YORK, N. Y., ASSIGNOR OF ONE-HALF TO JOSEPH P. RYAN, OF NEW YORK, N. Y.

NON-REFILLABLE BOTTLE.

1,113,652.

Specification of Letters Patent.

Patented Oct. 13, 1914.

Application filed May 10, 1913. Serial No. 766,780.

To all whom it may concern:

Be it known that I, BENJAMIN F. KLASS, a citizen of the United States, and a resident of the city of New York, borough of Bronx, 5 in the county and State of New York, have invented a new and Improved Non-Refillable Bottle, of which the following is a full, clear, and exact description.

This invention relates to an improved non-refillable bottle, that is, a bottle or vessel which, after its contents have been dispensed, cannot be refilled without destroying the bottle, thus serving as an effective means for preventing the sale of liquids or the like 15 unscrupulously.

The invention resides in the provision of a very simple combination of coöperating parts requiring but slight change in the construction of the bottle to provide for the 20 mounting of a float valve permitting the escape of the liquid or fluid but preventing refilling of the bottle, the parts being constructed of glass or similar vitreous material with the exception of the holding means for 25 a combined baffle wall and bearing disk for the valve.

With the above and other objects in view, the invention resides more particularly in the peculiar combination and arrangement 30 of parts which will be illustrated as a preferred embodiment in the accompanying drawings and described in the specification.

Reference is to be had to the accompanying drawings forming a part of this specification, in which like characters of reference indicate corresponding parts in all the views, and in which—

Figure 1 is a vertical sectional view 40 through a fragmentary portion of a bottle and parts mounted in the neck thereof to prevent the refilling of the bottle in accordance with the invention; Fig. 2 is a sectional view similar to Fig. 1 but showing the bottle tipped and with the valve in an 45 open position; and Fig. 3 is a plan view of the combined baffle wall and bearing disk, the same being partly broken away.

In the drawings, the numeral 5 designates the body of the bottle which is of glass or 50 other vitreous material in its preferred embodiment, and which is provided with a neck portion 6 ordinarily closed by a cork or other closure 7. In accordance with the present invention, the interior of the neck is 55 slightly tapered to provide a ground fit as

shown at 8, and the interior face of the neck at the juncture of the latter with the body is provided with an interior projection of beveled form producing a valve seat 9. Fitted in the neck and conforming to the portion 8 thereof is a combined baffle wall and bearing disk 10 which is also of glass or similar vitreous material, and which is preferably in the form of a pair of upper and lower sections 11 and 12 spaced apart but 60 formed in one through the instrumentality of a plurality of connecting strips or sections 13 spaced apart at the peripheral edge of the disk. Two of these strips, diametrically opposed, are provided with vertical recesses 14 and normally outwardly curved leaf springs 15 have their lower ends embedded in the lower sections 12 of the disk so that their upper ends will normally project outwardly of the peripheral edge thereof. 65 The purpose of this is to hold the disk in the neck of the bottle, and for this purpose the neck at diametrically opposed points interiorly is provided with notches 16 having their upper walls located at right angles to 70 the length of the neck and their side walls tapering in width downwardly so that when the disk is placed in the neck the springs will move into the recesses 14 until they are permitted to expand into the notches 16 and by 75 engagement of their extremities with the upper walls of the recesses, prevent the removal of the disk.

A valve 17 in the form of a hollow float 80 adapted, when submerged in the fluid which the bottle is designed to contain, to a point indicated by the line X—X in Fig. 1, has a tapered lower portion 18 of truncated form to coöperate with the seat 9 and normally close the neck of the bottle. The 85 weight of the valve and its upwardly extending stem 19 will depend upon the specific gravity of the fluid or liquid which the bottle is adapted to contain, and this stem passes through and is guided in a central opening 20 in the lower disk section 12 and a socket 21 communicating only with the lower face of the upper disk section 11, the upper end of the valve stem being movable in this socket, whereby it may be moved 100 to the open position indicated in Fig. 2 of the drawings.

The disk sections are provided with vertical passages or openings therethrough, the 105 passages 22 in the disk 11 being spaced apart 110

2
and preferably located nearer the center of the disk than the passages 23 through the lower section, so that the openings or passages in the respective sections of the disk are located in staggered relation to prevent the entrance of an instrument for holding the valve 17 open should an attempt be made to unscrupulously refill the bottle. To further prevent this, the passages terminate in extensions 24 and 25, the former depending into the space between the disk sections and the latter extending upwardly thereinto, thus providing shoulders serving to resist the entrance of a section wire or an instrument passed through the upper passages, into and through the lower passages.

In use of the bottle, the same is filled and with the valve mounted in the disk, the latter is shoved into the bottle neck and held by the springs as described. When it is desired to pour the contents of the bottle the liquid will elevate the float valve sufficiently to unseat it and permit the passage of the liquid, and the same will pass through the staggered passages and through the sections of the disk, but inasmuch as the liquid will be normally disposed below the valve, the latter will return by gravity to a closed position and seal the contents. It is of course understood that the cork 7 is removed when it is desired to pour the contents of the bottle. On the other hand, should an attempt be made to refill the bottle the pressure of the liquid on the top of the valve will hold it closed and the staggered relation of the openings, together with the extensions provided, will prevent the opening of the valve from the exterior. Furthermore, should it be attempted to fill the bottle by immersion, the liquid will pass through the passages, but in striking the valve the latter, by its floating action, will at once be seated to close the bottle neck and prevent the entrance of the liquid into the bottle. A very weak coil spring 26 is

mounted in the socket 21 to act on the stem 19 to assist in the seating of the valve, but not to prevent the valve from unseating under the pressure of the liquid when pouring the latter. The spring is not exposed to the liquid and therefore cannot contaminate the same.

Having thus described my invention, what I claim as new and desire to secure by Letters Patent is:—

1. A non-refillable bottle having a neck portion provided with an interior seat, a float valve having a stem, said bottle and valve being constructed of vitreous material, means to seat the valve, and a disk held in the neck against outward displacement and slidably receiving the stem of the valve for limited upward movement in unseating, said valve-seating means being carried by the disk, the disk embodying spaced upper and lower sections, said sections having passages therethrough located in staggered relation and terminating with extensions extending into the space between the sections.

2. A non-refillable bottle having a neck portion provided with a seat, a float valve having a reduced solid stem, means to seat the valve, and a disk held in the neck against outward displacement and slidably receiving the stem of the valve, said valve-seating means acting on the upper end of the stem and being inclosed by the disk, the disk having an interior opening providing upper and lower portions having passages therethrough, said passages terminating in extensions located within the area of the openings.

In testimony whereof I have signed my name to this specification in the presence of two subscribing witnesses.

BENJAMIN F. KLASS.
